[57] **CLAIM**

The ornamental design for a facade panel for a disk drive housing, as shown and described.

DESCRIPTION

FIG. 1 is a top perspective of the facade panel for a disk drive housing, showing the new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof; and,

FIG. 7 is a left side view thereof.

The broken lines showing a disk drive housing in FIGS. 1-7 are illustrative of environmental structure only, and form no part of the claimed design.

1 Claim, 5 Drawing Sheets

FIG. 2

FIG. 3
